Atty,

UNITED STATES PATENT OFFICE.

ABRAHAM M. HELLMAN, OF ST. LOUIS, MISSOURI.

METALLIC COVER FOR BARREL-HEADS.

SPECIFICATION forming part of Letters Patent No. 325,930, dated September 8, 1885.

Application filed June 27, 1885. (No model.)

To all whom it may concern:

Be it known that I, ABRAHAM M. HELLMAN, of the city of St. Louis, State of Missouri, have invented certain new and useful Improvements in Metallic Covers for Barrel-Heads, of which the following is a full, clear, and exact description, reference being had to the accompanying drawings, forming part of this specification, and in which—

10 Figure 1 is an end view of the barrel having my improved metal cover, and Fig. 2 is a detail section of the same.

My invention relates to a metal cover for barrel-heads, which is held in place by the head, 15 and which covers the entire surface of the head, preventing leakage in case of worm-holes in the head; and the invention consists in features of novelty hereinafter fully described, and pointed out in the claims.

20 Referring to the drawings, A represents part of the body of the barrel, and B the head, held in a croze, C, as usual. Outside of the head is my metallic cover D, which consists of a disk of metal the size of the head, and which 25 is held in place in the croze C by the head, as shown in Fig. 2. By thus securing the me-

tallic cover in place no part of it is exposed to the contents of the barrel to be affected thereby or to affect the contents in any undesirable way. In covering the entire outer face of the 30 head, as it does, it prevents leakage through the head in case of worm-holes or of irregularities in the joints of the head, and, moreover, it protects the head from exposure to the weather, so that it is not warped and shrunk, 35 as is frequently the case with unprotected heads. It also affords convenient means for any design that may be desired on the head of the barrel, as shown in Fig. 1, which can be simply impressed therein.

40 I claim as my invention—

In combination with the barrel having a wooden head, a metallic disk covering the entire outer surface of the head of the barrel and extending with the head into the croze, substantially as shown and described, for the 45 purpose set forth.

ABRAHAM M. HELLMAN.

In presence of—

GEO. H. KNIGHT,
SAM'L KNIGHT.
